UNITED STATES PATENT OFFICE

103,624

DESIGN FOR A SEAT

Ernie J. Beck, Chicago, Ill., assignor to S. Karpen & Bros., Chicago, Ill., a corporation of West Virginia

Application November 2, 1936, Serial No. 65,652

Term of patent 3½ years

To all whom it may concern:

Be it known that I, Ernie J. Beck, a citizen of the United States, residing at Chicago, county of Cook and State of Illinois, have invented a new, original, and ornamental Design for a Seat, of which the following is a specification, reference being had to the accompanying drawing, forming a part thereof, in which:

Fig. 1 is a side perspective view of a seat show-

ing my new design; Fig. 2, a rear view in elevation; and Fig. 3, a front view in elevation. The end of the seat opposite that shown in Fig. 1 is substantially identical in appearance with the end shown in Fig. 1.

I claim:

The ornamental design for a seat, as shown and described.

ERNIE J. BECK.
